STOCKING

Edwin Louis Schubert, Philadelphia, Pa.

Application March 31, 1949, Serial No. 1,739

Term of patent 14 years

(Cl. D47—7)

To all whom it may concern:

Be it known that I, Edwin Louis Schubert, a citizen of the United States, residing at Philadelphia, in the county of Philadelphia and State of Pennsylvania, have invented a new, original, and ornamental Design for a Stocking, of which the following is a specification, reference being had to the accompanying drawing, forming part thereof.

Figure 1 of the drawings represents a perspective view of a stocking of my new design, as said stocking appears when it is worn on the human leg.

Figure 2 represents a side elevational view of a portion of the stocking of my new design, as worn on the human leg.

Figure 3 represents a rear view of a portion of the stocking of my new design, as worn on the human leg.

I claim:

The ornamental design for a stocking, as shown.
EDWIN LOUIS SCHUBERT.
